UNITED STATES PATENT OFFICE.

HARRY E. CAMPBELL AND EARL F. MEKELBURG, OF MILWAUKEE, WISCONSIN,
ASSIGNORS TO UNION ELECTRIC MANUFACTURING COMPANY, OF MILWAUKEE,
WISCONSIN, A CORPORATION OF WISCONSIN.

ELECTRIC SWITCH.

Application filed August 3, 1925. Serial No. 47,809.

This invention relates to improvements in electric switches more particularly, although not solely adapted for drum type switches.

It is one of the objects of the present invention to provide an electric switch which is of very compact form to permit a number of the switches to be closely clamped together by a novel form of clamping means on supporting rods. The invention further 10 contemplates the independent removal of said switches for repairs or replacement without disturbing adjacent switches.

A further object of the invention is to provide an improved form of electric switch 15 in which the parts thereof are constructed almost entirely of stamped or commercial metal to form a switch which is of simple construction, is strong and durable, and which will secure a good electrical contact 20 with its cooperative contact members.

A further object of the invention is to provide an electric switch having means for eliminating any lateral and endwise movements of the contact finger during the operation 25 of the device.

With the above main and other incidental objects in view, the invention consists of the improved electric switch and its parts and combinations as set forth in the claims, and 30 all equivalents thereof.

In the accompanying drawing in which the same reference characters indicate the same parts in all of the views:

Fig. 1 is a sectional view of my improved 35 contact finger;

Fig. 2 is a transverse sectional view thereof taken on line 2—2 of Fig. 1;

Fig. 3 is a detail top view of some of the parts; and

Fig. 4 is a perspective view of the lever 40 arm member.

As the invention is particularly applicable to drum controllers the electric switch is shown as forming part thereof but it is 45 to be understood that the switch may be used for other types of switches.

Referring to the drawing, the numeral 5 indicates a segmental contact mounted upon a rotary drum; and positioned to engage the improved contact finger 6. The rotary drums of the drum controllers are usually provided with a plurality of segmental contacts for engagement with fixed contacts.

In the present instance the supporting rods 9 have the contact fingers 6 mounted thereon, said contact fingers engaging the respective drum contacts. 55

As the contact fingers are all alike only one is shown with its coating segmental contact. 60

The supporting rods 9 are insulated by tubular members 10 formed of some suitable insulating material. To the supporting rods 9 the switch is secured by a novel clamping means 12 comprising a clamping arm 14 having a right angular extension 14' forming a supporting base plate for the contact mechanism, and a cooperating clamping arm 13 substantially straight in construction and formed of any suitable metal and firmly held in clamping engagement with the supporting rods 9 by means of bolts 15 and nuts 16, and interposed between the nuts 16 and the clamping arm 14 split locking washers 17 are provided. Surrounding the bolts 15 and between the nuts 16 and 17 one end of a flexible conductor 18 is positioned and comprises a plurality of strips of copper, the other end of said flexible conductor being secured to the finger 6. A copper terminal portion 21 is also positioned between the same nuts 16 and 19 and has a tubular shaped end portion 21' for receiving a conductor wire therein. 70

The right angular extension 14' of this improved clamping arm has a fulcrum strip 22 riveted thereto which is formed with upwardly curved portions 23 and 20 and a stop portion 26. The portions 23 are bifurcated or spaced apart as shown in Fig. 3. 80 The curved portions 23 and 20 in connection with the clamping arm 14 form fulcrum openings or eyes and in the opening formed by the part 20, a rectangular link member 25 pivotally extends and a lever arm 24 extending through the said link member is provided with transversely extending side slots 24' through which the curved end portions 23 extend to pivot the lever arm to the clamping arm. The curved portions 23 are 85 spaced apart to receive the slotted portions of the arm 24 therebetween and to permit the curved portions 23 to extend outwardly through the side slots 24'. A contact finger 6 is mounted on the free end portion of the lever arm 24 and is connected thereto by 100 105

screws 33 and 34 which also bind the outer end of the flexible conductor 18 between the said lever arm and the contact finger 6.

A further novel feature of the invention 5 will now be referred to. The outer end portion of the lever arm 24 has a pair of downwardly extending guide lugs 30 which enter the recesses 71 formed at each side of the end of the clamping member 14 and recesses 10 31' correspondingly formed in the fulcrum strip 22, and an upwardly extending lug 28 positioned between the lugs 30 and entering the opening 29 in the contact finger 6. In this novel feature of the invention, these lugs 15 prevent lateral and endwise movement or turning of the contact finger during operation of the device.

The outer end portion of the contact finger 6 is formed with the usual enlargement 8 20 on its inner side which is of rounded formation and which bears against the drum segment 5 to form an electrical connection therebetween. A stop bolt 27 threaded through the contact finger 6 bears against 25 the stop portion 26 of the fulcrum strip 22 to limit the inward movement of said finger 6 when disengaged from the rotary contact 5. A yielding portion of a spring clip 32 engages the squared head 27' of the stop 30 screw 27 and holds said screw in adjusted position.

To maintain the contact finger 6 yielding in position an improved U-shaped readily detachable spring 35 with a hole 37 35 to accommodate the head of the screw 34 is positioned between the lever arm 24 and the outer portion of the rectangular link 25, while the outer end portion of the spring is formed with a hook like part 36 to receive 40 the outer portion of the rectangular link 25. The tension of the spring holds the parts in position and the contact finger in yielding engagement with the contact segment, and if it is desired to smooth off the face of 45 the finger, it is only necessary to disengage the spring from the link and swing the link to the right and the lever arm and the contact finger may be swung outwardly away from the segmental contact and expose the 50 working face of the finger for cleaning. Furthermore if it is desired to replace the finger it is only necessary to remove the screws 33 and 34 and the replacement may be easily made.

55 It is obvious that as the side edge portions of the fingers extend approximately in straight lines, a plurality of the fingers may be placed in parallel spaced relation quite closely together and any one of the fingers 60 may be repaired or replaced without disturbing the others.

From the foregoing description it will be seen that the electric switch is of simple construction, is strong and durable and is well 65 adapted for the purpose described.

It is also obvious that the different parts of the device are so constructed that they can be readily formed of stamped and commercial metal.

What we claim as our invention is:

1. An electric switch comprising a supporting means having two contacting portions, a single right angular clamping arm engaging said two contacting portions and having an outwardly extending tongue at 70 one end thereof, said tongue having recesses in the opposite side edges thereof, a single cooperating clamping arm also engaging said two contacting portions, a fulcrum strip mounted on said right angular clamping arm and having a stop portion at the outer end, a link member having one end portion pivotally carried between said fulcrum strip and the clamping arm, a lever arm also having one end portion pivotally carried between the fulcrum strip and the clamping arm, and provided with downwardly extending guide lugs engaging said 75 recesses of said outwardly extending tongue to prevent lateral and endwise movement of the lever arm, yielding contact mechanism carried by said lever arm, and a U-shaped spring interposed between a portion of the link member and the contact mechanism for 80 yieldingly holding the contact mechanism in 85 its inner position.

2. An electric switch comprising a supporting means having two contacting portions, a single right angular clamping arm engaging said two contacting portions and having an outwardly extending tongue at 100 one end thereof, said tongue having recesses in the opposite side edges thereof, a single cooperating clamping arm also engaging said two contacting portions, a fulcrum strip mounted on said right angular clamping arm and having a stop portion at the outer end, a link member having one end portion pivotally carried between said fulcrum strip and the clamping arm, a lever arm also having one end portion pivotally carried between the fulcrum strip and the clamping arm, and provided with downwardly extending guide lugs engaging said 105 recesses of said outwardly extending tongue to prevent lateral and endwise movement of the lever arm, yielding contact mechanism carried by said lever arm, a U-shaped spring interposed between a portion of the link member and the contact mechanism for 110 yieldingly holding the contact mechanism in 115 its inner position, a terminal member, conducting means, one end thereof being connected to said contact mechanism, and a common means for bringing the clamping arms into clamping engagement with the supporting means, and for securing the terminal member and one end of the conducting means together.

3. An electric switch comprising a sup- 120

porting base plate having an outwardly extending tongue at the end thereof, said tongue having recesses in the opposite side edges thereof, a lever arm pivotally mounted 5 on the base plate and provided with downwardly extending guide lugs engaging said recesses in said tongue, and yielding contact mechanism carried by said lever arm, lateral and endwise movement of the contact mechanism being prevented by the engagement of the downwardly extending lugs with the recesses in the opposite side edges of the tongue.

4. An electric switch, comprising a supporting means having two contacting portions, a single right angular clamping arm 15 engaging said two contacting portions and having an outwardly extending tongue at one end thereof, said tongue being provided 20 with recesses, a single cooperating clamping

arm also engaging said two contacting portions, a fulcrum member mounted on said right angular clamping arm, a link member having one end portion pivotally carried between said fulcrum strip and the clamping 25 arm, a lever arm also having one end portion pivotally carried between the fulcrum strip and the clamping arm, and provided with lug portions for engagement with the recesses in said tongue to prevent lateral and endwise movement of the lever arm, yielding contact mechanism carried by said lever arm, and a spring interposed between a portion of the link member and the contact mechanism for yieldingly holding the contact mechanism in normal position.

In testimony whereof, we affix our signatures.

HARRY E. CAMPBELL.
EARL F. MEKELBURG.
